UNITED STATES PATENT OFFICE

148,310

DESIGN FOR A CONTAINER FOR PERFUME BOTTLE OR SIMILAR ARTICLE

Lucien Lelong, Paris, France, assignor to Lucien Lelong, Inc., Chicago, Ill., a corporation of Illinois

Application May 13, 1946, Serial No. 129,669

Term of patent 14 years

(Cl. D58—12)

To all whom it may concern:

Be it known that I, Lucien Lelong, a citizen of the Republic of France and a resident of the city of Paris, France, have invented a new, original, and ornamental Design for a Container for Perfume Bottle or Similar Article, of which the following is a specification, reference being had to the accompanying drawing, forming a part thereof.

On the drawing:

Figure 1 is a top plan view of the container for perfume bottle, or similar article, showing my new design;

I claim:

The ornamental design for a container for perfume bottle or similar article, as shown.

LUCIEN LELONG.
